UNITED STATES PATENT OFFICE.

EDWARD L. CLARK, OF PITTSBURG, PENNSYLVANIA.

GAS-FURNACE.

SPECIFICATION forming part of Letters Patent No. 364,215, dated June 7, 1887.

Application filed April 3, 1886. Serial No. 197,601. (No model.)

To all whom it may concern:

Be it known that I, EDWARD L. CLARK, of Pittsburgh, in the county of Allegheny and State of Pennsylvania, have invented a new and useful Improvement in Gas-Furnaces; and I do hereby declare the following to be a full, clear, and exact description thereof, reference being had to the accompanying drawings, forming a part of this specification, in which—

10 Figure 1 is a side elevation of my improved furnace, part of the side wall being broken away for clearness of illustration. Fig. 2 is an end view of the furnace. Fig. 3 is an irregular horizontal section on the line $x-x$ of Fig. 1. 15 Fig. 4 is a vertical section of a part on the line $y-y$ of Fig. 3.

Like symbols of reference indicate like parts in each.

The object of the invention is to provide for 20 the construction of an improved and useful metallurgical furnace, in which gas is used as a fuel, and in which the air of combustion is heated before its admixture with the gas, the design of the furnace being to utilize the waste 25 heat of the furnace-walls as far as possible without interfering with the operations of the furnace.

To this end my invention consists, primarily, in the construction of a gas-furnace, with 30 an air-heating flue arranged in recurrent branches, which extend longitudinally in substantially the same horizontal plane under the furnace-bed, the advantages of which, as compared with those furnaces having a single 35 heating-flue under the furnace-bed, or a recurrent flue whose branches are not in the same horizontal plane, are that a greater amount of heat is absorbed by the air, and a better result is thereby obtained.

40 My invention consists, further, in other details of construction, which are specifically indicated in the claims.

The drawings show a heating or puddling furnace, in which 2 is the working-chamber, 45 and 3 is the bridge-wall which separates the chamber 2 from the combustion-chamber 4. The hearth of the working-chamber is a composite structure, consisting of a lower floor or bed, 5, of tile, which is preferably laid in two 50 or more courses, arranged to break joint the one with the other. Directly above the tile floor 5, back of the wall 3, are courses 6, of

fire-brick or other refractory material, and on this is superposed a layer, 7, of sand, both of which layers are of considerable thickness, as 55 shown in Fig. 1.

a and *b* are the air-heating flues, which have their adit at ports 8, situate at or near the end of the furnace and on opposite sides thereof. The flues *a* and *b* are bounded on their outer 60 sides by the exterior furnace-walls and on their inner sides by partition-walls *c* and *c'*, and are directly beneath the tile floors 5. At the rear end of the partition-walls *c* and *c'* the flues *a* and *b* communicate with return-flues *a'* and *b'*, 65 which are in the same horizontal plane with the flues *a* and *b*, and are likewise directly beneath the tile floor 5. At the end of the return-flues *a'* and *b'* they communicate with a compound vertical flue, *d d'*, which is constituted by a vertical deflecting-plate, 9, set in a space, 10, between the bridge-wall 3 and a vertical wall, 11, in front of the bridge-wall. A tile, 12, set over the space 10 forms the base of the combustion-chamber 4 and the top of the 75 flues *d* and *d'*. At the lower part of the flue *d* an exit-port, 13, through the wall 11, opens into the neck-flue 14 of the combustion-chamber, and a gas service pipe, 15, discharges thereinto at a suitable point, either above or 80 below the port 13. (See Fig. 4.) When thus constructed, the course of the air to the combustion-chamber is through ports 8, and thence along the flues *a* and *b*, under the floor 5, to the end of the furnace, and thence back through 85 the return-flues *a'* *b'* to the partition-plate 9, by which it is deflected upward through the flue *d* toward the tile 12, and thence down the diving-flue *d'* and through the port 13 into the neck-flue 14, where, mixing with the gas from 90 the pipe 15, combustion ensues, and from the combustion-chamber 4 the heated and burning gases enter the working-chamber 2. In its passage through these flues the air is exposed 95 to a considerable heat from several parts of the furnace. Thus, while in the flues *a* *b* and *a'* *b'* it is in contact with the tile floor 5, which is kept at a high temperature by conduction of heat from the working-chamber 2, and which in turn gives off its heat by radiation to the 100 passing air. The wall 3, being near the combustion-chamber and the heating-chamber and adjacent to the refractory layers 6 and 7, is normally kept very hot, as is also the tile 12,

which forms the bottom of the combustion-chamber, and is thus peculiarly exposed to heat. The air, therefore, in passing through the flues *d d'*, derives additional heat from these 5 parts, and on emerging into the combustion-chamber will be raised to a proper temperature to secure good combustion of the gas. The peculiar function of the diving-flue *d'* and its port 13, situate near the bottom of the wall 10 11, is that the air being thus drawn from the lower part of the flue *d'* is first deflected into more intimate contact with the heated tile 12 than if the flue *d'* were absent.

I do not claim, specifically, the arrangement 15 of the flues *d d'* and the covering-tile 12.

The advantage of the solid thick bed 5 6 7 over the ordinary thin metal bed heretofore in common use, in combination with an air-heating flue below it, is that while the passing 20 air in the flue is sufficiently heated for purposes of combustion it does not chill the furnace-bed and thus impede the metallurgical operations, as is apt to be the case when the metal bottom is used.

25 I am aware that, broadly speaking, I am not the inventor of a gas-furnace provided with recurrent air-flues underlying the bed of the furnace, nor of a composite furnace-bed, and I

disclaim the constructions shown in Letters Patent Nos. 296,398, 296,399, 310,454, 313,348, 30 179,033, and 9,715; but

What I claim as my invention, and desire to secure by Letters Patent, is—

1. The combination, in a gas-furnace, of a combustion-chamber, a gas-supply pipe opening into the combustion-chamber, and exterior air-heating flues, which extend underneath the furnace-bed from the end of the furnace to the rear thereof, and are there inwardly reflexed and extend to the combustion-chamber, preserving the same horizontal plane, substantially as and for the purposes described. 35

2. The combination, in a gas-furnace, of the composite furnace-bed consisting of a supporting-floor, 5, of tile, and a layer of refractory material directly overlying said floor, and a recurrent air heating flue directly underlying the composite bed, substantially as and for the purposes described. 45

In testimony whereof I have hereunto set 50 my hand this 26th day of March, A. D. 1886.

EDWARD L. CLARK.
